[57] **CLAIM**

The ornamental design for a combined meat smoker,
moisturizer and holder for wood chips, as shown and
described.

DESCRIPTION

FIG. 1 is a perspective view of a combined meat
smoker, moisturizer and holder for wood chips showing
my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is an end elevational view thereof, the opposite
end being a mirror image.

FIG. 1

FIG. 2

FIG. 3

FIG. 4

FIG. 5

FIG. 6
